MAGNETO IGNITION SYSTEM.

1,074,416.

Specification of Letters Patent. Patented Sept. 30, 1913.

Application filed June 5, 1908. Serial No. 436,963.

To all whom it may concern:

Be it known that we, JOHN M. DINKINS and FRANKLIN B. HAYS, citizens of the United States, residing at Indianapolis, in the county of Marion and State of Indiana, have invented certain new and useful Improvements in Magneto Ignition Systems, of which the following is a specification.

This invention relates to improvements in magnetos which are intended to generate a spark to explode the charge in an internal combustion engine, or for like purposes and the magneto shown in the drawings and hereinafter to be particularly described is specially adapted to four-cylinder engines for automobiles, launches, etc., but with different gear connections and wiring may be adapted to use on engines with a greater or less number of cylinders.

As magnetos generating a high-tension spark are easily affected as a rule by moisture, dirt, oil and other elements to which they are exposed one of the objects of our invention is to provide a machine which will be water, dust and oil proof.

Another object is to provide a machine which may be positively geared to the rotating parts of the engine thereby insuring a spark at the proper time in relation to the movement of the pistons.

Another object of our invention is to manually control the time of the spark to throttle the engine and utilize the combustible material entering the engine to best advantage without shifting the magnetic field of force of the magnets in relation to the position of the armature, and to provide pole-ends forming an integral extension of the magnet so as to add to the efficiency of the latter.

Another object of our invention is to provide a machine which is readily accessible, the magneto proper being easily disconnected from its base and its inner working parts all self-contained so as to be readily slipped out of the shell in which they are mounted.

Another object of the invention is to provide means for transforming a direct current from a separate set of batteries into an alternating current and permit the battery current to pass through the magneto at low speed to give sufficient spark for starting and running at low speed, and to provide automatic means for connecting

and disconnecting the battery current to meet the requirements of the running speed of the magneto and engine.

We accomplish the objects of our invention by the mechanism illustrated in the accompanying drawings, in which—

Figure 1 is a longitudinal central section of our improved magneto. Fig. 2 a transverse section on the line 2—2 of Fig. 1. Fig. 3 is a diagram showing the external wiring between our magneto and supplementary batteries and between the magneto and sparking-plugs of the engine. Fig. 4 is a transverse section on the line 4—4 of Fig. 1, and Fig. 5 is a detail in section in a plane longitudinally of the magneto, through the commutator.

Like characters of reference indicate like parts throughout the several views of the drawings.

Referring to Fig. 1 of the drawing, 8 represents the cylindrical body-portion of our machine to the ends of which are secured the external end caps 9 and inside partition and cap 10 in which the rotative parts are journaled. The armature is mounted on the shaft 12. The shaft 12 projects outside of the cap 9 and mounted thereon is the gear-wheel 15 which meshes with a corresponding gear on the engine proper. (Not shown.) Between the gear 15 and the armature and approximately near the end of the cap 9 is a commutator which will hereinafter be more fully described. Mounted on the shaft, that is forming an expanded portion of the shaft, is a drum 17 within which is mounted the condenser 18 of usual and well known construction. The drum 17 is cylindrical in shape and surrounding it is the annular collector ring 19 which is insulated from the drum by insulation 20. The armature is comprised of a series of laminated soft iron plates 21 which are thus used for the well known purpose of reducing the heat tendencies of the armature. These laminations 21 are assembled between the larger soft-iron members 22 and the assembled parts are united by means of the screw-bolts 23 in the manner shown in Fig. 1. The plates 21 and members 22 thus united are mounted between end-plates 24 and 25, preferably of brass, into which the ends of the divided shaft 12 are secured. The laminated plates 21 and end members 22 com-

prise the core of the armature which is provided with a primary winding of wire 26 and a secondary outer winding of finer wire 27. This secondary winding is for the customary purpose of acting as a transformer to increase the voltage.

30 represents the magnets used in our improved magnet which are of novel construction in the matter of their shape and in the location and arrangement of their pole-ends. The magnet is preferably of the laminated type and is here shown in three sections which are separated by means of insulation 31. The main body portions of the 10 laminated members are cylindrical in shape and fit snugly within the bore of the outside cylinder 8. The three laminated members 30 are assembled between outside plates 33 and are retained in position by means of 15 bolts 34 passing through the plates 33 and the space between the magnets and their pole-ends. It will be noted that a considerable space exists between the magnet-bodies 33 and the rotary armature which armature is located and rotates around the center or axial line of the magnet. As shown in Fig. 2 the pole-ends 35 of the magnets are curved into integral extensions which are located in the space between the cylindrical magnets and the armature. These pole-ends are suitably separated from the body of the magnets, except at their connections 37, with the magnet, and are curved to conform properly to the shape and rotary travel of the armature. By making our magnet of the cylindrical form here shown, we are able to bring it within the compass of the cylindrical body or shell 8, and by this cylindrical shape, in connection with the extensions of 20 the pole-ends around the armature in the space between the latter and the cylindrical magnets, we are able to obtain a magnet equal in length to that which is regarded as the standard of efficiency in other types of 25 magnetos, which could not otherwise be done in the limited space to which we are confined by our cylindrical construction. We are also able, by this construction of a magnet and pole-ends, to make both parts in one 30 piece and so establish the field of force as to conform to the rotary travel of the armature. The commutator is in the circuit of batteries which are used to reinforce the 35 magnets at low speed and during the major operations of the magneto, which are at high speed, the commutator and batteries will be cut out by means of a centrifugally 40 operated switch which will hereinafter be described.

45 The primary windings 26 of the armature will be grounded to the machine when the commutator and its batteries are disconnected. The other end of the primary winding passes through a circuit breaker and is 50 then grounded. This circuit breaker is

shown attached to the end-plate 24 of the armature by means of the screw 40 and comprises a pair of terminal plates 41 and 42. The plate 41 is insulated from the screw 40 and the machine. The terminal 42 is a 55 spring-acting plate which normally contacts with the end of plate 41. The plate 41 is one terminal of the primary winding 26. The terminals 41 and 42 are carried around by rotary movement of the armature and the 60 end of the plate 42 is bent to contact with the two diametrically opposed knobs 43 on the adjacent end plate 33 of the magnets 30, whereby said knobs, by contact with the end of plate 42, will force that plate out from 65 plate 41 so as to break the contact between the terminals 41 and 42, thus generating an induced current in the secondary winding 27. One terminal of the condenser 18 is connected with the terminal plate 41 and the 70 other terminal of the condenser is grounded thereby making a bridge over the spark-gap formed by the separation of terminal plates 41 and 42 when separated by the projections 75 43. The induced current generated in the 80 secondary winding is transmitted to the wire 44, to the collector ring 19, and thence through the brush 45 and through wire 46 to the brush 47 mounted in the end cap 48 at the other end of the machine. The brush 47 is in electrical contact with a metal cap 50 which is part of a rotary distributor. The metal cap 50 carries a brush 51 which is 85 brought into contact with suitably curved conducting plates 52 located in the path of said brush 51. The plates 52 are supported by the walls of the cap 48 and are suitably insulated therefrom as shown. As seen in Fig. 4 there are four conducting plates 52 arranged equi-distant around the inner circumference of the cap 48, and these plates are connected with binding posts 53 to which 90 wires 54 are attached. As shown in Fig. 3, the wires 54 are connected with sparking plugs 55 in the explosion chamber of the 95 engine.

The cap 50 of the distributor is carried by the insulation 56 on the end of the shaft 57. The shaft 57 is mounted on suitable ball-bearings 58 in the end of the cap 10, and mounted within the cap 10 on the end of the shaft 57 is the wheel 60 having side teeth which mesh with the teeth of an intermediate gear 61. The intermediate gear 61 is 100 loosely mounted on the shaft 62, which shaft is supported by the cap 10 and will preferably be mounted on ball-bearings as shown. The intermediate gear 61 is rotated by the gear 64 mounted on the adjacent end of the shaft 12. The relation of the gear 64 with the gear 60 is such that the gear 64 will 105 make two revolutions to each single revolution of the gear 60. The armature generates two electric impulses at each revolution and in order to furnish a spark to four 110

cylinders it is obviously necessary that the distributor travel half as fast as the armature. Hence the relation between the gears 64 and 60 as above stated. As the magneto 5 in starting and running at a low speed will not generate sufficient current to make the requisite ignition spark in the explosive cylinders unless its magnetic field is strong enough to generate an excess of current for 10 high speed which would cause undue heating, we provide the batteries 70 shown in Fig. 3 which have also been previously referred to. These batteries generate a direct current and as the magneto as above described generates an alternating current it is necessary to convert the battery current into an alternating current which will correspond with the current-flow generated by the armature. This is accomplished by the introduction of a two-piece commutator, which alternately reverses the polarity of the battery current as the current is transmitted into the armature. One of the pieces is represented at 5 and the other at 6, Figs. 1 and 15 25 30 35 40 45 50 55 60 65 70 75 80 85 90 95 100 105 110 115 120 125 130

As shown in Fig. 5, the shaft 12 is provided with a metal sleeve 75 having an annular outside end flange with oblique inner wall. The opposite end of the sleeve is screw-threaded to receive the nut 76, said nut having an oblique inner wall forming with the flange at the opposite end of the sleeve, a dove-tailed recess to engage and hold a correspondingly shaped portion of the two commutator parts 5 and 6. The parts 5 and 6 are insulated from the sleeve 75 and nut 76 by suitable insulation 77, and the two parts 5 and 6 are insulated from each other. The width of the insulation is more than the diameter of the brush to prevent the making of a short circuit by the brush. The member 6 of the commutator is grounded by the wire connection 78 as shown in Fig. 5. Wires 80 from the batteries connect with binding posts 81 supported by the cap 9 and these binding posts also carry the brushes 82 which contact with the commutator parts 5 and 6. The member 5 of the commutator carries and is electrically connected with the terminal plate 84, and mounted on the shaft 12 and insulated therefrom is the spring terminal plate 85 having its outer end bent in a direction longitudinally of shaft 12 and provided with a weight 86. On the other side of the terminal plate 85 from terminal 84 is the terminal plate 87 which is electrically connected with the shaft 12. By the rapid rotation of shaft 12 the terminal plate 85 will be moved centrifugally out of contact with the terminal 84 and into contact with the terminal 87 thereby automatically cutting out the battery at a predetermined speed of the armature which is regulated by the weight 86. The terminal plate 85 is connected by a wire 90 with the primary winding 26 of the armature.

The control of the time of the spark previously referred to as necessary to regulate the engine and utilize to best advantage combustible material entering the cylinders of the engine is accomplished manually by moving the magnets 30 in a rotary direction within its case by means of lever 92 which is connected with the magnet and extends outside of case 8, through a slot therein of appropriate length, to within reach of the operator. The control of the spark is thus provided for.

93 represents the base on which our machine is mounted. It has standards 97 which are shaped to conform to the cylindrical sides of the body 8 and said standards have a dowel-pin 98 to enter a suitable hole in the cylinder 8. A metal strap 96 has one end attached to the base 93 and passing thence around the body 8 is fastened to a nut 95 on bolt 94. The bolt 94 is supported by the base and has a projecting squared end 99 for the attachment of a key or wrench by means of which the bolt will be rotated thereby imparting a travel to nut 95 which will cause the strap 96 to be correspondingly loosened or tightened. The magneto proper is thus very easily disconnected from its base by thus loosening the metal strap 96, and the inner working parts of the magneto may be readily slipped out of the shell by unscrewing the brass end 9.

Having thus fully described our invention what we claim as new and wish to secure by Letters Patent of the United States, is—

1. An electric spark producing apparatus comprising a generator, a rotating armature therefor, primary and secondary windings on said armature, an external source of current, means for connecting said external source of current with said primary winding, and a commutating device in circuit with said external source to periodically change the polarity of said armature when the winding thereof is traversed by said external current.

2. In an electric spark producing apparatus, a generator comprising a rotating armature having a primary and secondary winding, an external source of current, and means for coupling said external current to the primary winding of said armature, said means including means adapted to change the polarity of said external current to conform to the polarity of the current generated in said primary winding, whereby the current in said primary winding is augmented by said external current and the induced current in said secondary winding maintained of a sufficient power to produce an efficient spark, substantially as set forth.

3. An electric spark producing apparatus comprising a generator including an arna-

ture having a primary and secondary winding, an external source of current, and means for connecting said external source of current to the primary winding of said 5 armature, including means for changing the polarity of said external current to conform to the polarity of the current generated in said primary winding, whereby the current in said primary winding is augmented by said external current, and the 10 induced current in said secondary winding maintained of sufficient power to produce an efficient spark, substantially as set forth.

4. An electric spark producing apparatus 15 comprising a generator including a rotating armature having a primary and secondary winding, an external source of current, and means controlled by the speed of the rotating armature for coupling said external 20 source of current to the primary winding of said armature and changing the polarity of said external current to conform to the polarity of the current generated in said primary winding, whereby when the speed 25 of said rotating armature falls below that necessary to produce the necessary current for an efficient spark in the secondary winding, said current will be augmented and maintained at such efficiency, substantially 30 as set forth.

5. In a magneto-generator, a cylindrical case, a permanent magnet conforming in shape to the cylindrical case and mounted therein, an armature rotating about an axis 35 which is at the center of said magnets, said armature having primary and secondary windings, an external source of current, and means for traversing the windings of the armature by said external current to change 40 the polarity of the armature.

6. In a magneto-generator, a cylindrical case, a permanent laminated magnet conforming in shape to the cylindrical case and mounted in 45 laminated sections rotating around an axis which axis is also the center of the annular magnets, said armature having primary and secondary windings, an external source of current, and means for traversing the windings of the armature by said external current to change the polarity of the armature.

7. In a magneto-generator, a cylindrical case, a permanent magnet conforming in shape to the cylindrical case and mounted 50 therein, an armature rotating around an axis which is at the center of said magnets,

said magnets having integral pole-ends formed on reverse arcs of smaller radius than the magnet body and located between the magnet body and the armature, said 60 armature having primary and secondary windings, an external source of current, and means for traversing the windings of the armature by said external current to change the polarity of the armature. 65

8. The combination, in a magneto, of permanent magnets, an armature, an auxiliary battery electrically connected with the armature, means for converting the direct current of the battery into an alternating 70 current and means for passing the alternating current through the magneto at a low speed of the latter.

9. The combination in a magneto, of permanent magnets, an armature, an auxiliary 75 battery electrically connected with the armature, a two-piece commutator between the battery and the armature for converting the direct current of the battery into an alternating current, and means for passing 80 the alternating current through the magneto at low speed of the latter and for cutting it off automatically at high speed.

10. The combination, in a magneto, of permanent magnets, an armature, an auxiliary 85 battery electrically connected with the armature, means for converting the direct current of the battery into an alternating current and a switch between the said converting means and the armature, said switch 90 rotating with the armature shaft and having a weighted terminal plate adapted to break the circuit by the centrifugal operation of said terminal plate at a predetermined speed. 95
